AIR PUMP -

Filed Nov. 7, 1944

INVENTOR,
Vernie E. Clarke.

UNITED STATES PATENT OFFICE

2,612,312

AIR PUMP

Vernie E. Clarke, Los Angeles, Calif., assignor to
Christine Association, Inc., a corporation of
California

Application November 7, 1944, Serial No. 562,364

1 Claim. (Cl. 230—185)

1

This invention relates to a combined compressor and vacuum pump, which in its functions has as its primary object, both the provision of means for the production of compression and vacuum simultaneously by means of reciprocating pistons positioned by means of sleeves on a unit piston rod within a plurality of cylinder chambers affixed end-to-end in line, separated by means of partition cylinder heads cast in with the cylinder walls on one end with a flange, and a flange on the other end thereof as means of fastening them together, means consisting of a plurality of valves, intake and outlet, within the partition cylinder head, for the purpose of admitting air by suction from a connected vacuum tank by means of two common manifolds connected to the several intake valves within the cylinder heads and for the purpose of compressing said air through the outlet valves and thence through a common manifold, affixed to the several outlet valves, into a compression tank, both of which compression tank and vacuum tank may be held in closed circuit for use, with means within the partition head for sealing the piston rod passage way, and means, externally, for reciprocating the piston rod and its several pistons, and a magnetic selective transmission for the purpose of controlling the rapidity of the reciprocating device and thus the impulses of the pistons.

Another object is the provision of means of positive, rapid and thorough action in exhausting air from a vacuum tank and transferring the air to a pressure tank which is smaller in size than the vacuum tank so that pressure and vacuum is created in the respective tanks simultaneously with the same device, with a minimum forward and backward stroke of the pistons within the multiple cylinder chambers end-to-end in line.

Another object is the provision of an economical source of power by means of compression and vacuum in closed circuit and so that a large volume of each, compression and vacuum may be stored for use in the development of applied mechanical power.

Another object is a compressor and a vacuum apparatus with the provision of a device so arranged that a shaft with a collar integrally positioned centrally lengthwise thereof with tapered bearings placed back to back on either side of said collar within a metal block with two bushing locks nuts screwed in, one on each end of said block, so that said shaft will not change its position laterally, horizontally, vertically or lengthwise, no matter in what position said apparatus is placed, means attached to said shaft for mov-

2

ing the pistons forward and backward, a casement with an inserted member therein, with a half spiral and reverse, a sliding piston with a dolly attached to follow in the spiral groove and reverse and thus when the casement and member inserted revolves the piston is reciprocated. The device is easily accessible for assembly and disassembly.

Still another object of my invention is to provide means of exhausting air and compressing air from and to respective receptacles with a comparatively short reciprocating motion to operate said apparatus without requiring an excessively powerful driving motor.

15 A further object is the provision of a combined compressor and vacuum apparatus of the general character herein described which is very simple and economical to manufacture, install and operate and so compact that it requires relatively small space for installation.

20 My invention possesses other objects and advantageous features some of which with those enumerated will be set forth in the following preferred embodiment of my invention illustrated in 25 the drawing accompanying and forming part of the specifications.

It is understood that I do not limit myself to the showing made by the said drawing and specification, as I may adopt variations of the preferred form within the scope of my invention as set forth in the claim.

30 Referring to the drawings:

Fig. 1 is a view of the complete apparatus.

35 Fig. 2 is a view of a complete cylinder and partition cylinder head assembly.

Fig. 3 is a view of the thrust bearing, shaft and reciprocating device.

Fig. 4 is a view of the cylinderhead assembly for the last cylinder in the alignment.

40 Referring to the drawings more specifically in which corresponding reference characters indicate corresponding parts in the several views, 45 indicates one of the plural metallic cylinders, which is fitted with flanges 15 and 16. Flange 16 is attached to the outer end side of the cylinder partition head 17 which is recessed at 55 to receive a projection of flange 15 at 56. The cylinder partition head 17 has placed in it a straight hole 18, located on a radius midway between the outside periphery of partition member 17 and a center hole 19. A circular hole 20 intersects hole 18 midway of its length from the outside periphery of member 17.

50 Installed in hole 18 is a spring 21, a ball 22 and a ball 23, one on each end of spring 21 and ball

22 is held in place by a bushing 24 against ball 22 and a bushing 25 against ball 23. Both of 22 and 23 act as outlet valves.

At the outside end of hole 20 are installed a nipple 26, a union 27, a nipple 28 in the union 27, and inserted severally into the common manifold 29, which is connected by a nipple 30, inserted into a check valve 31, a nipple 30A from check valve 31 to a compression tank 32, upon which is mounted an indicating gauge 33, and an outlet line 34 provided with a shut off valve 35 to hold pressure in tank 32, or to release pressure at will.

A circular hole 36 extends half way through the partition 17 which intersects hole 37 at right angles, and another hole 38 drilled half way through member 17 intersected by a hole 39 placed at right angles thereto and enters member 17 at a point 90 degrees removed from hole 20 on the outside periphery of member 17. In hole 37 is placed a circular screen 40 inserted to the bottom of hole 37, and a spring 41 with a ball valve 42 held in place by a machined nipple 43, fitted with a union 44 to a nipple 45 which are severally screwed into a common manifold 46, which manifold 46 is connected by a nipple 47, a check valve 48, a nipple 49 inserted into the vacuum tank 50, upon which is a vacuum gauge 51. An inlet pipe line 52 and a valve 53 is provided to open or close the inlet from the outside of tank 50 at 54. The outlet at 34 on the compression tank 32 may be connected with the line at 54 on compression tank 50 to form a closed circuit between the two tanks 32 and 50.

Likewise at hole 39A in member 17 is inserted a circular screen extending to the bottom of 37 within which is placed a spring with a ball valve 42A urged by the spring against a nipple machined to fit ball valve 42A and to hold it in place. The nipple is connected by means of a union to a second nipple which is screwed into a common manifold 46A.

The flanges 15 and 16 are each fitted with bolt holes 58 to receive bolts 57 so that a plurality of cylinders 14 may be assembled end-to-end in line.

The open end of cylinder 14 is provided with a flange 15 with a projection insert 15A, to which is fitted a cylinder head 17 with a hole 18A half way through intersecting a hole 20A extending at right angles to the outside periphery of 17, and a hole 39A is drilled to intersect hole 38A drilled half way through member 17.

The end partition cylinder head 17 of the last installed cylinder is fitted with a plate 17A with bolt holes 58 to receive bolts 57 so as to attach to flange 16A. The outside hole 18A is fitted with a face plug 60, thus blocking off hole 18A on the outside end thereof.

Each successive partition cylinder head 17 is provided with a hole 19 therethrough in its center portion, and with two face bushings 62 and 62A which are circularly grooved on the inside and designed to be inserted one from one side and the other from the other side of said member 17 so that there is a cavity 63 between said bushings. In a hole 64 in the outside periphery of member 17 at a point 45 degrees removed from hole 37 is inserted a grease fixture 65 through which grease is forced as a seal to the reciprocating rod 66 upon which is mounted the several pistons 67 equipped with pistons rings 67A and positioned by sleeves 68 within the several cylinder compartments 69.

Exteriorly of the vacuum compressor apparatus, both ends of the piston rod 66 are threaded

ends 70 and 70A fitted at both ends with sleeves 68A. End 70 is screwed into an annular member 71, drilled and threaded at 71A to receive end 70 of said piston rod and adapted to reciprocate in an annular aperture fixture 72 which is provided with two grooves 72A, guides to receive members 71B which are attached to member 71 to prevent member 76, rod 66 and pistons 67 from rotating. Interiorly of member 71 are affixed a dolly 73, which is adapted to operate in a helical groove 74, and a rotating member 76 which is mounted on one end of a shaft 77, which is provided with dividing collar 78 separating two taper roller bearings 84 and 87 opposed to each other and arranged in cups 80 and 82 both of which are positioned within a block 83 by means of insert lock nuts 85 and 88.

When shaft 77 rotates it causes member 76 with 74 to also rotate, which in turn causes member 71, which is fitted interiorly with a dolly 73 set on a fixed pin 73A that travels in spiral 74 thereby causing annular member 71, the piston rod 66 affixed thereto, and pistons 67 to reciprocate without rotating.

End 70A of said piston rod 66 is provided with a lock washer 91, a lock nut 92, a lock washer 93 a lock nut 94 adapted to tighten and to firmly hold all members on said rod firmly fixed in position within the several piston chambers 69.

In the operation of my invention, power is applied to the rotating shaft 77 and member 76 causing member 71 to move back and forth thus actuating the piston rod 66 together with the several pistons 67 mounted thereon within the several compartments 69 between the several cylinder head partitions 17. The pistons 67, fitted with rings 67A are so arranged that they have an efficient suction as well as compression as they are forced back and forth within the several compartments 69. When said pistons reciprocate a vacuum is created on one side of them and a compression on the other side. When the piston 67 moves forward the intake port at 36 opens with vacuum and at 25 with compression and when the piston 67 moves backward then the port at 38A opens with vacuum and at 24 by compression. When vacuum is created air is exhausted from vacuum tank 50 and compressed into compression tank 32.

Thus it will be seen that vacuum and compression is created by this apparatus embodied in my invention simultaneously with each stroke of the pistons within the cylinder compartments.

While I have shown and described a specific embodiment of my invention, I do not limit myself to the exact details of construction and arrangements shown, but may employ such changes and modification as occasions may require coming within the scope and meaning of the appended claim.

I claim:

In combination, a concurrent air pressure and vacuum device as described having a plurality of aligned cylinders, a piston within each of said cylinders, a single piston rod connecting said pistons; a rigidly exteriorly affixed annular casing on one end of the said plural cylinders in alignment, grooves longitudinally affixed 180 degrees apart to the interior walls of said annular casing; a non-rotatable reciprocating annular member with means exteriorly thereof to engage said grooves, and means to attach the said non-rotatable reciprocating annular member to the piston rod of said device, a rotatable cylindrical member having a helical groove in the cylindrical surface

thereof, means on the interior walls of said reciprocating member to engage the said helical groove, means to position said rotatable member rigidly longitudinally within said reciprocating member so that said reciprocating non-rotating member may be reciprocated in performing its functions aforesaid in the operation of said air pressure vacuum device.
